STAKEHOLDER FOR RAILWAY FLAT CARS

Thomas William McAuley, North Bay, Ontario,
Canada

Application October 14, 1932, Serial No. 637,819

3 Claims. (Cl. 105—383)

My invention relates to improvements in stake holders for railway flat cars, and the object of the invention is to devise a simple, cheap and quickly operable holder whereby the stakes may be released in a minimum amount of time and with a minimum amount of effort, and it consists essentially of the arrangement and construction of parts as hereinafter more particularly explained.

Fig. 1 is a perspective view of a flat car body intermediately broken away of its length and showing my stake holders applied thereto.

Fig. 2 is an enlarged plan sectional view of the stake holder and stake.

Fig. 3 is a plan sectional view through the stake holder on the same scale as Fig. 2 showing the holder in the closed position in full lines and in the open position in dotted lines.

Fig. 4 is a vertical sectional view through the centre of the stake holder.

In the drawing like letters of reference indicate corresponding parts in each figure.

1 indicates the body of a flat car provided with stake holders secured to the side of the car, these 25 stake holders each comprise a socket member 2 consisting of a back plate portion 2^x, from which extend forwardly upper lug members 3 and 4 and lower lug members 5 and 6. The lug members 3 and 4, and 5 and 6 form the side portions 30 of the socket between which the stake 7 fits, the lower end of the stake resting, at its inner edge, upon a slightly inward extension 5^x as clearly indicated by dotted lines in Fig. 2.

By this means it will be seen that a socket member 35 having an open front is provided. 8 and 9 are jaw members comprising a vertically set bar-like body secured to rods forming end pintles 8^x and 9^x pivotally mounted respectively in the upper and lower jaw members 3 and 5, 4 and 6. The 40 rear side of the body is formed concentric with the pintles 8^x and 9^x.

The outer face of the back plate 2 is preferably inclined outwardly from the upper to the lower end of the socket so as to give a corresponding 45 inclined pitch to the inserted stake. The body members 8 and 9 of the jaws are provided with inwardly extending upper and lower opposing gripping pieces 10 and 11, preferably situated at the upper and lower ends of the bodies 8 and 9, such 50 pieces extending inwardly at right angles to such body members so that, when they are in the closed position, they bear against the outer face of the stake.

12 are bearings of any suitable form in which 55 is mounted a longitudinal movable rod 13 having

an end slot 13^x. 14 is a collar secured to the rod 13 and provided with inwardly extending lugs 14^x and 14°. The pintles 9^x are provided with downward extensions having horizontally turned ends 10^x and 11^x having longitudinal slots 10° and 11° overlapping one over the other in their locking position.

15 is a link provided with a jawed end, the members of which extend above and below the portions 10^x and 11^x and through which and the slots 10° and 11° extends a pin 16. The opposite end of the link 15 is also provided with a jawed end between the members 17^x and 17° of which the collar 14 fits, such collar being provided with pintles 17 diametrically set and on which the members 17^x and 17° of the link 15 are pivoted. The members 17^x and 17° are provided with internal bosses 18 and 19 having semicircular faces bearing against the lugs 14^x and 14°.

The rod 13 is moved longitudinally by means 75 of a lever 20 having an arm 21 extending through the slot 13^x, its movement being limited by the stop 21^x. 22 is a locking pin extending through an orifice in the timber 1^x in front of the main arm of the lever 20 so as to positively hold the 80 mechanism in the locked position.

When the parts are in the position shown in the drawing with the stake inserted as shown in Fig. 2 the link 15 bearing against the portions 10^x and 11^x at one end and against the lugs 14^x and 14° at the opposite end definitely locks the members 8 and 9 in the locked or stake holding position. When the rod 13 is moved by the lever 20 in the direction of arrow the parts are carried to the dotted position as shown in Fig. 3 and 85 swing the members 8 and 9 to the open position also indicated by dotted lines in Fig. 3 releasing the stake which is then forced out of the socket by the weight of the load.

From this description it will be seen that I 90 have devised a very simple means whereby the stakes of the flat car may be readily released by a single quick movement of the operator, the load on the side of the car of the released stakes 95 forcing such stakes outward so as to swing the jaw members 8 and 9 to their open position and thereby allowing the stakes to fall clear releasing the load.

What I claim as my invention is:

1. In a stake holder, a socket member comprising a back plate, horizontal upper and lower lugs extending from each side of the back plate and a stake rest extending from the bottom of the back plate, a stake holding member 110

20 pivoted between each pair of lugs, a longitudinally slidable rod carried in stationary bearings, and means operated by the longitudinal movement of the rod for swinging the stake holding members 5 to and from their stake holding position.

25 2. In a stake holder, a socket member comprising a back plate, horizontal upper and lower lugs extending from each side of the back plate, a stake rest at the bottom of the back plate, a 10 stake holding member pivoted between each pair of lugs, opposing arms extending transversely of the back plate and carried by such pivoted members, a longitudinally movable rod slidably mounted in stationary bearings, an operating lever 15 therefore, and means connected to the opposing arms and operated by the longitudinal movement of the rod for swinging the stake holding members to and from their stake holding position.

3. In a stake holder, a socket member comprising a back plate, horizontal upper and lower lugs extending from each side of the back plate, a stake rest at the bottom of the back plate, a stake holding member pivoted between each pair of lugs, opposing arms extending transversely of the back plate and carried by such pivoted members, a longitudinally movable rod slidably mounted in stationary bearings, an operating lever therefore, a collar secured to the longitudinally movable rod, and a link pivotally connected to the collar at one end and a pin extending through the opposite end and through the longitudinal slots of the arms of the opposing members.
